UNITED STATES PATENT OFFICE.

HARRY VERCOE HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY.

ANVIL-BLOCK LUG CHUCK.

Application filed July 14, 1921. Serial No. 484,707.

To all whom it may concern:

Be it known that I, HARRY V. HAIGHT, a citizen of the Dominion of Canada, a resident of Sherbrooke, Province of Quebec, Canada, have invented a certain Anvil-Block Lug Chuck, of which the following is a specification accompanied by drawings.

This invention relates to fluid actuated rock drills of the hammer type, but more particularly to an anvil block lug chuck for drills of that type.

In those cases in which the hammer piston strikes directly upon the end of the shank of the drill steel, trouble is sometimes experienced because of the chipping of the striking face of the piston. This trouble may in some cases be due to poor piston shanks, but protection for the piston has been afforded by permitting the piston to strike upon an anvil block instead of directly upon the shank of the steel.

The objects of the present invention are to enable an anvil block to be interposed between the piston and the shank of lug steel, that is, a steel having lugs on the shank, and for this purpose I have devised an anvil block lug chuck which may be readily assembled and disassembled for the insertion and removal of the anvil block, is strong and rugged in construction and has parts which are not liable to become broken or distorted in use.

Further objects of the invention will hereinafter appear and to all of these ends the invention consists of the anvil block lug chuck illustrated in some of its preferred forms in the accompanying drawings, in which—

Figure 1 is a side view partly in longitudinal section of a rock drill having my lug chuck applied thereto,

Figure 2 is a transverse sectional view of Figure 1 on the line 2—2 looking in the direction of the arrows and also on the line 2—2 of Figure 3,

Figure 3, is a view similar to Figure 1 of a modification,

Figure 4, is a transverse sectional view of Figure 3 on the line 4—4 looking in the direction of the arrows,

Figure 5, is a longitudinal sectional view partly broken away of a modified form of the anvil-block lug chuck, and

Figure 6, is a transverse sectional view on the line 6—6 of Figure 5.

Referring to the drawings, the cylinder A of the rock drill, the front head B and the handle C which in this instance also forms the back head, are held together by the usual side bolts D. A hammer piston, of which only the forward reduced and fluted shank E is shown, reciprocates in the cylinder A, and imparts blows of impact to the drill steel F, the shank of which extends into the front head. A valve casing G adapted to contain a suitable distributing valve is secured to the cylinder A as by means of the bolts H, and motive fluid is supplied at the inlet J and exhausted at the exhaust port K.

In accordance with my invention, I have devised a form of chuck particularly adaptable for receiving an anvil block L interposed between the hammer piston E and the lug steel F, for protecting the piston, the usual lugs on the steel being indicated at O. Suitable provision is made for readily and conveniently assembling and disassembling the parts so that the steel may be inserted and withdrawn as required in the usual construction and so that the anvil block may also be quickly inserted or changed.

Referring at first more particularly to Figure 1, a chuck key P is located within the forward end of the front head B against the flange Q and formed with an opening K elongated in a plane at right angles to the plane of the section of Figure 1 for permitting the shank of the steel and the lugs O to be inserted through the key, and turned so that the lugs may bear against the shoulders S formed within the forward cavity or jaw T in the jaw half of the rotating chuck, or jaw member U removably secured to the remaining portion of the chuck formed by the rotating chuck member or nut half V. The chuck key P is formed with lugs or projections W engaging a transverse recess X in the end face of the chuck jaw U for maintaining the key and chuck jaw in proper alignment as they rotate together.

The jaw half or chuck jaw U is preferably in the form of a pierced forging for strength and lightness, and in Figure 1 the nut half V and jaw half U are threaded together by means of the internal screw threads Y on member V cooperating with the external screw threads Z on the reduced portion a of the member U. When the parts are adjusted and tightened in position the member

V has a bearing against the shoulder b on the chuck jaw U.

The nut half V of the chuck is in the form of a sleeve having a bore c in which the anvil block L is located and when the chuck members U and V are unscrewed, the anvil block may be readily and conveniently inserted in or removed from the chuck member V. Rearward movement of the anvil block is limited 10 by the integral shoulder d formed at the rearward end of the bore c and this shoulder forms a solid abutment which is not liable to break or become deformed with use. By removing the front head B with the chuck parts, the anvil block L may be readily removed from the chuck after the chuck member V is removed from the front head B, without first removing the chuck jaw U and chuck key P from the front head.

20 Any suitable means may be provided for imparting rotation to the chuck as for instance, rifle bar rotation, but I have only shown that portion of the rotation comprising the slidable but non-rotatable connection 25 between the forward fluted shank E of the hammer piston and the nut half V of the chuck to indicate that rotation is imparted to the chuck. An internally fluted chuck nut e is threaded into the rearward end of the 30 nut half V of the chuck for engaging the external flutes on the piston shank and a front cylinder washer f surrounds the parts as indicated.

With the construction shown in Figure 1 35 the chuck members may be unscrewed and separated when the front head is removed, but in view of the fact that difficulty may sometimes be experienced in jamming of the threads between the two chuck members, 40 the modifications of the construction shown in Figures 3 to 6 inclusive may be preferred.

In the modification shown in Figure 3 the jaw half g of the chuck is formed of a pierced forging, as in Figure 1 but is somewhat differently constructed at its rearward end, in order that this jaw half g may be clutched to the nut half h of the chuck instead of being screw threaded thereto as in Figure 1. The jaw half g is provided with a rear recess j for receiving the anvil block L and is also provided with clutch jaws k cooperating with clutch members p on the nut half h of the chuck. An internal shoulder o is formed on the nut half h for limiting the rearward movement of the anvil block. In other respects, the construction of the anvil block lug chuck is like that indicated in Figure 1, but the chuck members may be more readily assembled and disassembled 55 because of the simple sliding clutch engagement between said members.

In the modification shown in Figure 5, internal flutes q are provided at the forward end of the nut half r of the chuck, adapted 60 to engage external flutes s on the jaw half

w of the chuck so that these parts have non-rotatable engagement but may be readily assembled and disassembled.

I claim:

1. A rotatable anvil block lug chuck for 70 rock drills of the hammer type, adapted to impart rotation to the lug steel, comprising a front head, two chuck members therein removably but nonrotatably engaging 75 each other at their meeting portions, one member having a jaw at its forward end for receiving the shank and lugs of the lug steel, the other member having an integral shoulder at the rearward end of the bore of said member forming an abutment, a removable anvil block located within the chuck member having the said shoulder for receiving and imparting the blows of impact to the drill steel, and a chuck key in the front head connected to one of said chuck members to rotate therewith, said anvil block being adapted to be removed from the chuck member in which it is located after the front head is removed from the machine without removing said chuck key and jaw member 80 from the front head.

2. A rotatable anvil block lug chuck for 90 rock drills of the hammer type, adapted to impart rotation to the lug steel, comprising a front head, a jaw member having a jaw 95 adapted to receive the shank and lugs of the lug steel, a chuck member having an integral shoulder at the rearward end of the bore of said member forming an abutment, said chuck member removably and non-rotatably engaging said jaw member, a removable anvil block located within said chuck member having the shoulder and adapted to receive and transmit the impact blows of the hammer piston to the drill steel, and a chuck key in the front head connected to said jaw member to rotate therewith, said anvil block being adapted to be removed from the chuck member in which it is located after the front head is removed from the machine without removing said chuck key and jaw member 100 from the front head.

3. A rotatable anvil block lug chuck for 105 rock drills of the hammer type, adapted to impart rotation to the lug steel, comprising a front head, a chuck key in the front head through which the shank of the drill steel extends, a jaw member removably and non-rotatably engaging said chuck key and having a jaw adapted to receive the shank and lugs of the lug steel, a chuck member having an integral shoulder at the rearward end of the bore of said member forming an abutment, said chuck member removably and non-rotatably engaging the rearward portion 115 of said jaw member, a removable anvil block located within said chuck member having the shoulder and adapted to receive and transmit the impact blows of the hammer piston to the drill steel, said anvil block 120

being adapted to be removed from the chuck member in which it is located after the front head is removed from the machine without removing the chuck key and jaw member 5 from the front head.

4. A rotatable anvil block lug chuck for rock drills of the hammer type, adapted to impart rotation to the lug steel, comprising a front head, a jaw member having a jaw 10 adapted to receive the shank and lugs of the lug steel, a chuck member having an integral shoulder at the rearward end of the bore of said member forming an abutment for limiting the rearward movement of an anvil block, said chuck member removably and

non-rotatably engaging said jaw member, a removable anvil block located within said chuck member having the shoulder and adapted to receive and transmit the impact blows of the hammer piston to the drill steel, 20 and a chuck key in the front head connected to said jaw member to rotate therewith, said anvil block being adapted to be removed from the chuck member in which it is located after the front head is removed from the machine without removing said chuck key and jaw member from the front head.

In testimony whereof I have signed this specification.

HARRY VERCOE HAIGHT.
